[57] CLAIM

The ornamental design for a dispenser case for a contact lens cleaning fabric, substantially as shown and described.

DESCRIPTION

FIG. 1 is a perspective view of a dispenser case for a contact lens cleaning fabric showing my new design;

FIG. 2 is an enlarged top plan view thereof;

FIG. 3 is an enlarged left side elevational view thereof,

the right side being a mirror image;

FIG. 4 is an enlarged front elevational view thereof;

FIG. 5 is an enlarged rear elevational view thereof;

FIG. 6 is an enlarged bottom plan view thereof.

FIG. 1

FIG. 2

FIG. 3

FIG. 4

FIG. 5

FIG. 6
